HYDRAULIC TIMING MEANS

James V. Brady, New York, N. Y., and William I. Hamilton, Hackensack, N. J., assignors to Lanova Corporation, Long Island City, N. Y., a corporation of Delaware

Application June 3, 1952, Serial No. 291,412

4 Claims. (Cl. 64—25)

This invention relates to means for varying the angular relation between a drive shaft and a shaft driven thereby, for timing the injection or admission of fuel in internal combustion engines, and analogous purposes.

Injection or diesel engines are quite sensitive to the timing of the injection of fuel. It is desirable for most efficient operation of injection engines, particularly engines operating over a wide speed range, to advance and retard the injection timing in accordance with increase and decrease in engine speed. Injection timing devices are known. In general, the known devices are rather complicated and expensive in construction, lack sensitiveness in operation and often are inadequately lubricated.

Our invention is directed to means for varying the angular relation between a drive shaft and a shaft driven thereby, particularly suitable for use as injection timing means, but suitable also for other purposes. The drive shaft has driving connection to the driven shaft through a hydraulic servo-motor effective for varying the angular relation between the shafts. As used with injection engines, the drive shaft is driven from the engine shaft, the driven shaft is the operating or cam shaft of the injection pump, and the servo-motor is controlled by valve means. The valve means is adjustable responsive to the speed of the drive shaft, to provide automatic adjustment of injection timing. The control valve means comprises a control valve adjustable relative to the housing and the rotor of the servo-motor, the rotor being turnable relative to the housing and the control valve. The latter and a sleeve valve turnable with the rotor, and the drive shaft, are provided with cooperating ports and ducts or passages for admitting and discharging operating hydraulic fluid to and from the servo-motor effective for turning the rotor in proper direction to an appropriate extent for effecting and maintaining desired angular adjustment of the driven or pump cam shaft relative to the drive shaft. Conveniently, the operating hydraulic fluid is the engine lubricating oil delivered by the usual oil pump from the engine crank case sump to the servo-motor under substantial pressure. The servo-motor is provided with means for preventing clogging thereof by dirt contained in the oil and is also provided with means guarding against movement of the rotor relative to the housing due to variations in torque required to drive the injection pump shaft, which is maximum at the instant of injection and then rapidly falls to a minimum. All of the moving parts of the servo-motor and the control valve and associated parts operate in oil so that no appreciable friction occurs, which is conducive to sensitiveness and accuracy in operation. Further objects and advantages of our invention will appear from the detail description.

In the drawings:

Figure 1 is a lengthwise central vertical sectional view, taken substantially on line 1—1 of Figure 2, of injection timing means embodying our invention, certain parts being shown in elevation and certain other parts being shown partly in elevation and partly broken away and in section, the injection pump being shown fragmentarily and the

2

parts being shown in the positions which they occupy when the injection pump cam shaft is in full retard position;

Figure 2 is an end view of the timing means of Figure 1, with the housing cover plate removed and the housing shown fragmentarily, with the parts in the positions which they occupy when the cam shaft of the injection pump is in full retard position;

Figure 3 is a sectional view taken substantially on line 10 3—3 of Figure 1;

Figure 4 is a sectional view taken substantially on line 4—4 of Figure 1;

Figure 5 is a sectional view taken substantially on line 15 5—5 of Figure 1;

Figure 6 is a sectional view taken substantially on line 6—6 of Figure 1;

Figure 7 is a sectional view similar to Figure 3, but with the parts in the positions which they occupy at advanced position of the injection pump cam shaft;

Figure 8 is a sectional view similar to Figure 4, but with the parts in the positions which they occupy at advanced position of the pump cam shaft;

Figure 9 is a sectional view similar to Figure 4, but with the parts in the positions which they occupy when 25 the injection pump shaft is in retard position; and

Figure 10 is a sectional view similar to Figure 3, but with the control valve and the other parts in the positions which they occupy in Figure 9.

Our instant invention is in the nature of an improvement over the hydraulic timing means of the copending application of James V. Brady, Serial No. 255,091, filed November 6, 1951. In the timing means of our instant invention admission of oil to, and drainage of oil from, the servo-motor is controlled by the control valve and a sleeve valve turnable with the rotor. The control valve is piloted in the sleeve valve, the latter is piloted in the head of the drive shaft, and the passages or ducts for supplying oil to, and draining oil from, the servo-motor are in the head of the drive shaft. With that arrangement, 30 but two ports and a groove, in the control valve, and four ports, in the sleeve valve, are required, regardless of the number of vanes on the rotor. That is conducive to accuracy in indexing of the ports in the control valve and in the sleeve valve, which is of importance. Further, the 35 passages or ducts for supplying oil to, and discharging oil from, the servo-motor are arranged in two groups, those of one group opening into a common channel in the head of the drive shaft and those of the other group opening into another and separate channel in the head of the drive shaft. That avoids necessity for precision in 40 drilling the passages or ducts in the head of the drive shaft, thereby reducing expense and assuring accuracy in operation. An additional and important advantage of 45 our invention is that the control valve and the drive shaft may be quite short so that possibility of bending and binding of parts, due to any slight misalignment or distortion, such as might be caused by the drive gear thrust, is effectively guarded against. That eliminates binding and 50 objectionable wear of parts and renders it possible to reduce clearances to a minimum thereby reducing oil leakage to a minimum, which is conducive to sensitivity and accuracy in operation.

The timing means of our invention is particularly suitable for use with injection engines and will be so described, though in its broader aspects it may be used for other purposes, as above noted. We have shown the timing means of our invention, by way of example, as used with an injection pump 20, which may be any suitable known pump, having a casing 21 and an operating cam shaft 22 rotatably mounted in ball bearings 23. A cylindrical casing 24 is bolted to one end of the pump

casing 21, about an annular flange 25 thereof, with an intervening sealing O ring 26. The casing 24 is coaxial with cam shaft 22 and is bolted at its other end to an inner plate 27 of a casing 28 which extends upwardly from and opens downwardly into the crank case (not shown) of an injection engine with which the injection pump 29 is associated. The casing 28 is provided with a front wall or plate 29 having a circular opening therein about which is disposed an annular collar 30 on the outer end of which seats a cover plate 31, this plate 31 and collar 30 being bolted or otherwise suitably secured to front wall 29 of casing 28.

The outer end wall 33 of casing 24 is thickened and is provided with an outwardly extending annular flange 34 about which plate 27 seats, and with an axial bore in which is mounted a bearing bushing 35. A tubular drive shaft 36 is rotatably mounted through bushing 35 and is provided with radial inlet ports 37 opening interiorly thereof and opening at their outer ends into an interior circumferential groove 38 in the bushing 35. The shaft 36 extends outward beyond plate 27 and has its outer end portion slightly reduced in diameter to provide a shoulder against which seats a flanged collar 40 keyed on shaft 36 and restrained against outward movement thereon by a thimble 41 threaded into the outer end of shaft 36 and provided at its outer end with a head 42, there being a washer 43 confined between head 42 and the outer end of collar 40. A gear 44 seats on flange 45 of collar 40 and is suitably secured thereto, conveniently by bolts 46. This gear 44, in practice, is driven, through suitable gearing, from the engine crank shaft so that the shaft 36 is driven at predetermined speed relative to the engine crank shaft; as is known.

The bolts 46 pass through an annular clamping and reinforcing plate 48 seating on the web of gear 44 and, in cooperation with the bolts 46, clamping it tightly against flange 45. A substantially oblong arm 49 is keyed on the outer end of a control valve 50 mounted for relative turning movement in drive shaft 36 and extending outward therebeyond. The arm 49 is recessed at its mid-length for reception of a spring washer 51 confined between arm 49 and head 52 of a cap screw 53 threaded into the outer end of control valve 50. The outer end portion of control valve 50 is slightly reduced in diameter, as shown in Figure 1, to provide a shoulder between which and the washer 51 arm 49 is confined. Two oppositely disposed fly weights 54, shown more clearly in Figure 2, are pivoted at their outer ends, at 55, on the clamping plate 48, the studs or pivots 55 being secured to plate 48 and projecting an appropriate distance outward therebeyond. Posts 56 are pivotally mounted on weights 54 radially inward thereof beyond the pivot studs 55 and a tension spring 57 extends between and is anchored at its ends to the posts 56. Pins 58 are secured in the fly weights 54, adjacent the ends thereof remote from the pivot studs 55, and extend through oppositely disposed cam slots 59 in the end portions of arm 49. As will be understood from what has been said, the tension spring 57 urges the fly weights 54 toward each other and, when the drive shaft 36 is not rotated, or is rotated at a speed corresponding to or less than the full retard angular position of the pump cam shaft 22 relative to drive shaft 36, as will be explained more fully later, pulls the fly weights 54 into their innermost positions, with the pins 58 at the inner ends of the cam slot 59, as shown in Figure 2. When the speed of rotation of drive shaft 36 is increased to or beyond a predetermined value, which may be termed its advance injection speed, as will be explained more fully later, the fly weights 54 swing outward in opposition to the tension spring 57 and the pins 58, in cooperation with the cam slots 59, turn the arm 49 and thereby turn the control valve 50. The cam slots 59 are so disposed that arm 49 is turned clockwise, as viewed in Figure 2, by outward movement of fly weights 54 and is turned counterclockwise by inward movement

thereof. Accordingly, the control valve 50 is turned clockwise responsive to increase in speed of rotation of the drive shaft 36 and is turned counterclockwise responsive to decrease in the speed of rotation of drive shaft 36, within the speed range thereof from full retard injection to full advance injection.

The control valve 50 is provided with an outer circumferential shoulder 61 confined between the inner end of thimble 41 and an interior shoulder of shaft 36, effective for restraining control valve 50 against endwise movement in either direction while permitting free turning thereof within shaft 36. A plug 62 is threaded into and closes the inner end of a bore in the control valve 50 extending from the inner end thereof, providing an admission chamber 63 for operating hydraulic fluid, as will be explained more fully later. The control valve 50 is provided with a reduced bore or inlet duct 64 extending from the outer end of chamber 63 and with inlet or admission ports 65 opening radially outward from duct 64 into an annular space 66 surrounding control valve 50, as will appear more fully later.

The bearing bushing 35 is provided with an admission port 67 which opens into an admission passage 68 in end wall 33 of casing 24. The outer end portion of passage 68 is enlarged and threaded to receive the threaded end portion of a tube 69 connected to a suitable source of supply of operating hydraulic fluid under appropriate pressure. In practice, the tube 69 is connected to the discharge of an oil pump of suitable known type, which withdraws oil from the sump of the engine crank case and delivers it under appropriate pressure to tube 69. Referring further to Figure 1, the inner end of admission duct 64 is formed to provide a seat for a ball check valve 70 urged in closing direction by a compression spring 71 confined between valve 70 and plug 62, for a purpose which will be described later.

The drive shaft 36 is provided, at its inner end, with an enlarged frusto-conical head 66 and a cylindrical head 72 comprising a cylindrical body or barrel 73 within which are disposed a suitable number—six being shown—of abutment elements 74 of approximately sector shape. These abutment elements 74 fit tightly against the inner circumferential face of barrel 73, are spaced apart circumferentially thereof and extend radially inward of barrel 73. An annular flanged closure plate or ring 75 fits tightly in the inner end of barrel 73 and is secured therein by bolts 76 passing through head 66 and through the abutment elements 74 and threading into plate 75. The barrel 73 is positioned axially by flanges 77 and 78 of head 66 and plate 75, respectively, and abutment elements 74 are clamped tightly between plate 75 and head 66 and are held accurately in position thereby and by the bolts 76.

The head 72 provides a cylindrical housing closed at its ends for reception of a rotor 80 shown more clearly in Figures 1 and 6. This rotor 80 comprises a central cylindrical hub 81 and vanes 82 integral with and extending radially outward from hub 81 into the spaces 83 between the abutment elements 74. The outer end of hub 81 of rotor 80 has a sealing, but not tight, fit against the flat inner face of head 66 of drive shaft 36. Hub 81 also has a sealing, but not tight, fit between the inner ends of the abutment elements 74, and the inner end of hub 81 has a sealing, but not tight, fit against the flat outer face of the end closure plate 75. The vanes 82 of rotor 80 are of substantially less thickness than the width of the spaces 83 between the abutment elements 74 and have a sealing, but not tight, fit with the circumferential wall of barrel 73 and with the inner face of head 66 and the outer face of the end closure plate 75.

The hub 81 is bored out from its outer end to provide an outlet chamber 85. The inner end of hub 81 is splined on the outer reduced end of cam shaft 22 of the injection pump 29. Chamber 85 receives the head of a cap screw 91 threaded into the end of cam shaft 22, there

being a retaining ring 92 and a lock washer 93, of suitable known type, confined between the head of screw 91 and an interior shoulder of hub 81 for restraining the latter against outward movement lengthwise of cam shaft 22, hub 81 being restrained against inward movement by the inner race of the ball bearing 23, as will be clear from Figure 1. The hub 81 is provided with suitably disposed discharge ducts 94 extending therethrough from the inner end of chamber 85 of rotor 80, for discharge of the hydraulic operating fluid or oil from chamber 85 into the casing 24, as will appear more fully later. The oil is discharged from the lower portion of casing 24 through an opening 95 in end wall 33 of casing 24 and thence downward through casing 28 into the crank case of the engine.

The frusto-conical head 66 of drive shaft 36 is provided with a first set of substantially radial ducts 98 with their radially outer ends opening through the inner face of head 66 at one side of the vanes 82 into the spaces 83 between the abutment elements 74. Head 66 is further provided with a second set of substantially radial ducts 101 with their radially outer ends opening through the inner face of head 66 into the spaces 83 between the abutment elements 74 and at the sides of vanes 82 opposite to those at which the ducts 98 are located.

The drive shaft 36 is bored out from its inner end to receive a sleeve valve 86 fitting snugly, but not tightly, in shaft 36 and over the inner end portion of control valve 50, the latter being piloted in sleeve valve 86 and sleeve valve 86 being piloted in shaft 36 with the latter piloted thereon. The sleeve valve 86 is provided with two upper ports 87 and 88 and two lower ports 89 and 90, spaced apart lengthwise thereof. The ports 87 and 89 open into an inner circumferential channel 96 in head 66 of drive shaft 36, and the ports 88 and 90 open into a second inner circumferential channel 97 in head 66. The outer end of sleeve valve 86 is spaced from the outer end of the bore in shaft 36, to provide the space 66 about control valve 50, previously mentioned. The sleeve valve 86 is provided, at its inner end, with two diametrically opposite slots 99 and 100 which receive a key 102 fitting snugly therein and in diametrically opposite grooves in the outer end of hub 81 of rotor 80. The sleeve valve 86 is thus attached to rotor 80 for rotation therewith and is restrained against relative axial movement, by hub 81 of rotor 80 and by the pressure of the oil in space 60 on the outer end of sleeve valve 86. The slot 100 is extended so as to overlap the inner end portion of a lengthwise drainage or discharge groove or passage 103 in the outer face of control valve 50, at the lower portion thereof as shown in Figure 1. The groove 103 is of approximately the same width as the respective ports 89 and 90 and of a length to bridge both thereof.

The control valve 50 is further provided, at the opposite side thereof from groove 103, with two radial ports 105 and 106 extending from the admission chamber 63, disposed in the same transverse planes as the channels 96 and 97, respectively. The abutment members 74 are provided at one side of the outer ends thereof with recesses 107 aligned with the ducts or passages 98 of head 66 of drive shaft 36, and at the opposite sides of their outer ends with recesses 108 aligned with the ducts or passages 101, for admitting oil under pressure to the servo-motor at one side of the vanes 82 of rotor 80 while draining oil from the other side of vanes 82, as will be explained more fully presently.

When the drive shaft 36 is not rotating, or is being driven at a speed less than that requiring advancement of injection, the rotor 80 is in its full retard position, in which the leading faces of the abutment elements 74 are in contact with the vanes 82 of rotor 80, it being understood that the shaft 36 is driven clockwise as indicated by the arrow in Figure 2. The control valve 50 is then also in its maximum counterclockwise or retard position and both of the ports 105 and 106 thereof are then closed

5 at their radially outer ends by sleeve valve 86, and groove 103 is closed to ports 89 and 90 of sleeve valve 86, by control valve 50, as will be clear from Figures 3 and 4. The rotor 80 is then driven from the drive shaft 36 through the direct mechanical driving connection provided by the abutment elements 74 and the vanes 82, and the angular relation between the drive shaft 36 and the injection pump cam shaft 22 remains unaltered.

10 Referring to Figures 7 and 8, upon increase in speed of rotation of the drive shaft 36 to a value requiring advancement of injection, the fly weights 54 move outward in opposition to tension spring 57, under the influence of centrifugal force, turning the control valve 50 in clockwise direction. This turning of the control valve 15 50 brings port 105 into communication with port 87, while maintaining groove 103 closed to port 89. Oil then flows under pressure from the admission chamber 63 into channel 96 and thence through ducts 98 into the servo-motor, between the abutment elements 74 and the 20 vanes 82 of rotor 80. The entering oil exerts pressure upon the corresponding faces of the vanes 82 and turns the rotor 80 in clockwise or injection advance direction relative to the associated housing. That advances the 25 angularity of the injection pump cam shaft 22 relative to the drive shaft 36 thereby advancing the timing of injection to the desired extent corresponding to the engine speed. When the desired advancement of injection has been effected, the turning of sleeve valve 86 on the 30 control valve 50 substantially closes the radially outer end of the port 105, leaving it cracked slightly open for a purpose to be described presently.

35 During clockwise turning of rotor 80 relative to the enclosing housing, the oil at the opposite sides of the vanes 82 from the ducts 98 is displaced and passes through ducts 101 into channel 97 and thence through port 90 and groove 103 into the outlet or discharge chamber 85 of rotor hub 81, from which the oil flows through ducts 94 into casing or housing 24 and is returned to the engine crank case as previously described. As will be 40 understood, when the radially outer end of the port 105 of control valve 50 is uncovered by turning thereof, the radially outer end of the port 106 remains closed by sleeve valve 86 and groove 103 is opened to port 90, as shown in Figure 8. If the speed of rotation of drive shaft 36 continues to increase, the control valve 50 will be turned a further distance clockwise and that may continue until the maximum speed of rotation of drive shaft 36 is reached and the maximum advancement of injection has been attained, at which time the rotor 80 will have been turned into its maximum advance position. When the rotor 80 has been turned, clockwise relative to drive shaft 36, a distance corresponding to the speed of rotation of shaft 36, with corresponding turning of the sleeve valve 86 about control valve 50, the ports 105 and 90 are cracked open. That is desirable in order to maintain oil under appropriate pressure in the spaces between the vanes 82 and the elements 74, in the event of slight leakage about the vanes, since the drive between the housing and the rotor is then through the oil confined between the vanes 82 and elements 74. As will be 55 understood from what has been said, the rotor 80, and with it the injection pump cam shaft 22, may be advanced to any desired extent, within limits, relative to the drive shaft 36. The rotor 80 and its enclosing housing and associated parts thus constitute a servo-motor controlled by the control valve 50 and the sleeve valve 86 and responsive to the speed of rotation of the drive shaft 36 and, therefore, responsive to engine speed, for automatically advancing the timing of injection in accordance with increase in speed of rotation of drive shaft 36.

60 When the speed of rotation of drive shaft 36 decreases, the control valve 50 is turned counterclockwise thus opening port 106, closing groove 103 to port 90, closing port 105, and opening the port 89 to the groove 103, as shown in Figures 9 and 10. Oil then flows through ducts 101

under pressure into the servo-motor at one side of the vanes 82 thus turning the rotor 80 in counterclockwise direction, the oil at the opposite sides of the vanes being discharged through ducts 98, channel 96, port 89 and groove 103 into the discharge chamber 85, from which it is delivered into the casing 24 and thence into casing 28 and downward into the engine crank case, as before. This counterclockwise turning of rotor 80 reduces the angle of advancement of the injection pump cam shaft relative to the drive shaft 36, thereby retarding the timing of injection, as will be understood. If there is no further decrease in the speed of rotation of drive shaft 36, the counterclockwise turning of rotor 80, and with it sleeve valve 86, closes the ports 88 and 106, and closes port 89 to groove 103, ports 87 and 105 being then cracked slightly open to supply make-up oil to the rotor 80 in replacement of oil which may leak past the vanes 82, and port 90 also being then cracked slightly open to groove 103 to drain off the oil leakage; thus maintaining the angular adjustment between the shafts 36 and 22. If the speed of rotation of drive shaft 36 continues to decrease, the continued turning movement of control valve 50 counterclockwise maintains the ports 88 and 106 open and the port 89 open to groove 103, while maintaining ports 87 and 105 closed and port 90 closed to groove 103, until the rotor 80 is returned to full retard position, at which time all of the ports 106, 90, 105 and 89 are again closed, as before.

As will be seen, from what has been said, the servo-motor, under control of the control valve 50, is effective for advancing and retarding the timing of injection responsive to increase and decrease in the speed of rotation of the drive shaft 36, throughout the range of turning movement of the rotor 80 relative to the servo-motor housing. In general, an angular adjustment of approximately fifteen degrees of the rotor 80 relative to its associated housing is sufficient, though that angle may be varied to suit conditions. Also, by varying the cam slots 59, the rate of adjustment, or advancing or retarding of the timing of injection, may be adjusted or set to suit any particular engine.

In the operation of the injection pump, the peak torque required occurs at the instant of injection and then falls off rapidly to a minimum. Accordingly, at the instant of injection there would be a tendency to force oil from between the vanes 82 and the abutment members 74 back into and through the admission chamber 63 of the control valve 50, unless that were guarded against. The check valve 70, urged in closing direction by the compression spring 71, shown in Figure 1, guards against back flow of oil through chamber 63 and is conducive to accuracy in operation of the servo-motor in the manner above described.

The oil or other operating hydraulic fluid delivered to the servo-motor is apt to contain a certain amount of dirt, such as carbon and other impurities. Such impurities are urged toward the circumferential wall of the housing of the servo-motor, during rotation thereof, by centrifugal force, and are removed therefrom through the passages or ducts 98 or 101 and the corresponding channels and ports of the drive shaft 36, sleeve valve 86 and control valve 50, and groove 103 of control valve 50, as will be understood from what has been said. In that manner, dirt which would tend to accumulate within the servo-motor and might cause clogging thereof to such an extent as to interfere objectionably with its accuracy in operation, is continuously removed therefrom, which is conducive to accuracy in the timing of injection. It will also be noted that the movable parts of the servo-motor, including the control valve 50, operate in oil, which eliminates friction and resultant wear and further contributes to accuracy and ease of operation. The ducts 98 and 101 open into the channels 96 and 97, respectively, so that precision in drilling of those ducts is not required. Operation of the servo-motor is controlled by but four

ports in the sleeve valve 86 and two ports and the groove 103 in control valve 50, all of which are spaced well apart and may be precisely indexed without difficulty, which is conducive to accuracy in operation. Further, by providing the sleeve valve 86, the drive shaft 36 may be quite short so as to avoid risk of bending and binding of parts, thereby reducing necessary clearance and resultant oil leakage to a minimum.

The timing means of our invention is particularly suitable for timing the injection in injection engines, and has been described as used for that purpose, by way of example. In its broader aspects, however, it may be used for varying the angular relation between a drive shaft or member and any driven shaft or member. Accordingly, the driven shaft may be, for example, a cam shaft for actuating the valves of an aspiration internal combustion engine receiving fuel-air mixture from a carburetor or other suitable source, or any other shaft or member which it is desirable to adjust for timing purposes.

As above indicated, and as will be understood by those skilled in this art, changes in detail may be resorted to without departing from the field and scope of our invention, and we intend to include all such variations, as fall within the scope of the appended claims, in this application in which the preferred form only of our invention has been disclosed.

We claim:

1. In means for varying the angular relation between two shafts, a driven shaft, a tubular drive shaft coaxial with said driven shaft, a servo-motor providing driving connection between said shafts comprising a housing fixed to said drive shaft and a rotor within said housing fixed to said driven shaft, said housing having circumferentially spaced abutment elements fixed thereto extending inwardly thereof, said rotor having vanes extending between said elements, said drive shaft having two interior inwardly opening circumferential channels spaced apart axially thereof and two sets of ducts respectively opening into said channels, the ducts of one set opening into said housing at one side of said vanes and the ducts of the other set opening into said housing at the other side of said vanes, a control valve concentric with said drive shaft turnable relative thereto and having a discharge passage, and a sleeve valve cooperating with said control valve concentric with said drive shaft and turnable with said rotor about said control valve, said valves having cooperating ports effective for admitting operating hydraulic fluid to one of said channels and connecting the other thereof to said discharge passage and vice versa responsive to turning of said control valve in one direction and in the other direction respectively relative to said drive shaft.

2. In means for varying the angular relation between two shafts, a driven shaft, a tubular drive shaft coaxial with said driven shaft, a servomotor providing driving connection between said shafts comprising a housing fixed to said drive shaft and a rotor within said housing fixed to said driven shaft, said housing having circumferentially spaced abutment elements fixed thereto extending inwardly thereof, said rotor having vanes extending between said elements, said drive shaft having two interior inwardly opening circumferential channels spaced apart axially thereof and two sets of ducts respectively opening into said channels, the ducts of one set opening into said housing at one side of said vanes and the ducts of the other set opening into said housing at the other side of said vanes, a control valve concentric with said drive shaft turnable relative thereto and having an admission chamber and a discharge passage, and a sleeve valve concentric with said drive shaft and turnable with said rotor about said control valve, said valves having cooperating ports effective for opening one of said channels to said chamber while closing it to said passage and closing the other of said channels to said chamber while opening it to

said passage and vice versa responsive to turning of said control valve in one direction and in the other direction respectively relative to said drive shaft.

3. In means for varying the angular relation between two shafts, a driven shaft, a tubular drive shaft coaxial with said driven shaft, a servomotor providing driving connection between said shafts comprising a housing fixed to said drive shaft and a rotor within said housing fixed to said driven shaft, said housing having circumferentially spaced abutment elements fixed thereto extending inwardly thereof, said rotor having vanes extending between said elements, said drive shaft having two interior inwardly opening circumferential channels spaced apart axially thereof and two sets of ducts respectively opening into said channels, the ducts of one set opening into said housing at one side of said vanes and the ducts of the other set opening into said housing at the other side of said vanes, a control valve in said drive shaft concentric therewith turnable relative thereto and having an interior admission chamber and an exterior discharge passage, and a sleeve valve fitting in said drive shaft and about said control valve and turnable with said rotor about said control valve, said valves having cooperating ports effective for opening one of said channels to said chamber while closing it to said passage and closing the other of said channels to said chamber while opening it to said passage and vice versa responsive to turning of said control valve in one direction and in the other direction respectively relative to said drive shaft.

4. In means for varying the angular relation between 30

two shafts, two coaxial shafts, a servo-motor providing driving connection between said shafts comprising a housing fixed to one of said shafts and a rotor within said housing fixed to the other shaft and turnable in either direction relative to said housing, said one shaft being tubular and having two interior inwardly opening circumferential channels spaced apart axially thereof and two sets of ducts respectively opening into said channels for admitting and exhausting operating fluid to and from said housing, a control valve in said one shaft concentric therewith turnable relative thereto and having an interior admission chamber and an exterior discharge passage, and a sleeve valve fitting in said one shaft effective for closing the inner sides of said channels and fitting about said control valve and turnable thereabout with said rotor, said valves having cooperating ports effective for opening one of said channels to said chamber while closing it to said passage and closing the other of said channels to said chamber while opening it to said passage and vice versa, responsive to turning of said control valve in one direction and in the other direction respectively relative to said one shaft.
